CHARLES E. OATHOUT, OF CLEVELAND, OHIO, ASSIGNOR TO THE KAYNEE COMPANY, OF CLEVELAND, OHIO, A CORPORATION OF OHIO.

BUTTONHOLE-TAPE.

1,336,577.

Specification of Letters Patent. Patented Apr. 13, 1920.

Application filed April 21, 1919. Serial No. 291,516.

To all whom it may concern:

Be it known that I, CHARLES E. OATHOUT, a citizen of the United States, residing at Cleveland, in the county of Cuyahoga and State of Ohio, have invented a certain new and useful Improvement in Buttonhole-Tape, of which the following is a full, clear, and exact description.

This invention relates to a button-hole tape adapted to be attached to garments to enable the latter to be buttoned to companion garments, and the invention has for its object to provide a button-hole tape so formed that the liability of the button-holes tearing out is reduced, and also to provide a tape which effects a saving or economy in material. In other words, it is the aim of the invention to provide a button-hole tape which is better and stronger than those which have been on the market heretofore, and which can be formed as cheaply, and possibly more cheaply than the latter.

The invention may be briefly summarized as consisting in certain novel features of construction, and arrangements of parts which will be described in the specification and set forth in the appended claims.

In the accompanying sheet of drawings, Figure 1 is a view of a portion of a garment to which a section of my improved button-hole tape is attached; Fig. 2 shows a section of the tape as it is formed in accordance with my invention; Fig. 3 is a similar view of the tape partly formed, this view showing especially the manner in which the material is folded to form the plies and showing also the location of the button-holes and of the reinforcing strip; Fig. 4 is a sectional view through the tape to show the manner in which it is preferably attached to the garment illustrated in Fig. 1, this view being on an enlarged scale; and Figs. 5 and 6 are enlarged sectional views substantially along the lines 5—5 and 6—6 of Fig. 2.

My improved button-hole tape is formed from a continuous strip of material 10, which can be of indeterminate or indefinite length. This strip is folded longitudinally to form three plies 11, 12 and 13, one line of fold being shown at F in Fig. 3, and the other line of fold being indicated at F'. This forms the three plies, with the ply 12 between the two plies 11 and 13. The free edge of ply 11 is extended beyond the fold

F', to form an attaching section 14 by which the tape is sewed to a garment, a portion of which is shown at 15 in Figs. 1 and 4.

Between the plies 12 and 13, next to or adjacent the fold F', I provide a reinforcing strip 16, and the button-holes themselves, which are shown at 17, are formed or worked only in the two plies 12 and 13, and they extend from the reinforcing strip 16 downward toward the opposite edge of the tape, the lower ends being just above the inner free edge of that part of the strip forming the ply 13. Two points of importance to be noted, are that the button-hole slits do not include any part of the reinforcing strip 16, and the button-holes are formed in just two thicknesses or plies of material.

The reinforcing strip is attached to the two plies 12 and 13, by a line of stitching indicated at 18, and after the reinforcing strip is inserted and attached, and the button-holes are formed, the strip of material is folded along the line F', previously referred to, to form the ply 11, and then the tape is completed by a sinusoidal or undulating line of stitching 19, which passes through all three plies, and which extends beneath the button-holes and upwardly between them to about the lower edge of the reinforcing tape 16, as clearly shown in Figs. 1 and 2. As will be apparent, this line of stitching forms open-topped pockets, one for each button-hole, allowing for the insertion of the fingers to button or unbutton the garment.

These tapes are generally made in long lengths, and will generally be wrapped on a spool, reel or other holder until ready for use. In using this tape in the manufacture of garments it will be cut into suitable lengths such as illustrated in Fig. 1, and in attaching a section to a garment, the free edge or attaching portion 14 of ply 11 is first sewed to the garment by a line of stitching, shown at 20 in Fig. 4, the free edges of both the garment and the attaching portion 14 of the tape being preferably folded in, as shown in this figure, and then the opposite or lower edge is attached to the garment by a line of stitching shown at 21.

The reinforcing strip is so located that it effectively resists stresses set up by the pull on the buttons, and since the edge of the reinforcing strip next to the button-holes is not slit in the formation of the button-

holes, it is obvious that this reinforcing strip is of uniform strength from end to end; that is to say, it is uncut selvage at both edges, and hence is of maximum strength, it being very obvious that this strip has far greater resistance to tearing, and that the button-holes can withstand far greater pull than would be the case if the inner or lower edge of the reinforcing strip 10 were notched or slit in the formation of the button-holes.

By having the button-holes formed in the two plies only, wholly outside of the reinforcing strip, not only is the most effective 15 reinforcement obtained, but the button-holes are formed in the same number of plies or from the same thicknesses of the material from end to end, which is very desirable from a manufacturing standpoint.

Having described my invention, I claim:

1. A button-hole tape formed from a strip of material folded longitudinally to form three plies, a reinforcing strip between two of the plies and located adjacent one 25 edge of the tape, and a series of spaced button-holes formed in the inner and one outer ply of the tape wholly beyond the reinforcing strip.

2. A button-hole tape formed from a strip of material folded longitudinally to form three plies, a reinforcing strip located between two of the plies and extending lengthwise of the tape along one edge thereof, said two plies having a series of spaced button-holes, and the third ply in which the button-holes are not formed having its free edge portion extending beyond the other two plies to form an attaching section.

3. A button-hole tape formed from a strip 40 of material folded longitudinally to form

three plies, a series of spaced button-holes formed in two of the plies only, a reinforcing strip located between said two plies and wholly between the folded edge forming the latter and the button-holes, said reinforcing 45 strip and the two plies being secured together by a line of stitching, and the three plies being secured together by a line of stitching extending beneath the button-holes adjacent one edge of the tape and upwardly 50 between the button-holes.

4. A button-hole tape formed from a strip of material folded longitudinally to form three plies, the free edge of one of which extends beyond the other two plies to form 55 an attaching section, said other two plies having button-holes formed therein, and a reinforcing strip between said last mentioned plies and located wholly between the upper ends of the button-holes and the adjacent edge of the tape, the three plies being fastened together by an undulating line of stitching which passes below the button-holes and upwardly toward the reinforced 60 edge, forming between the first mentioned 65 ply and the middle ply, open-topped pockets.

5. A button-hole tape formed from a strip of material folded longitudinally to form three plies, the middle ply including one margin of the strip, a reinforcing strip inside the folded portion of the folded strip between the middle ply and one of the outer plies, and button-holes formed wholly beyond the reinforcing strip in the two plies 70 between which the reinforcing strip is located.

In testimony whereof I hereunto affix my signature.

CHARLES E. OATHOUT.
